Primary Examiner — Richard Edgar*Assistant Examiner* — Jessica Ruth Grable(74) *Attorney, Agent, or Firm* — Warner Norcross + Judd LLP(57) **CLAIM**

The ornamental design for an overbed table as shown and described.

DESCRIPTION

FIG. 1 is a top, left, front perspective view of the overbed table embodying the new design;

FIG. 2 is a bottom, left, front perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof; and,

FIG. 9 is an enlarged view of Area 9 of FIG. 2.

FIGS. 1-8 show portions of an overbed table in broken lines. The (dash-dash) broken line portions do not form part of the claimed design. The (dash-dot) broken lines shown in FIGS. 2 and 9 are included for the purpose of illustrating the boundary of enlargement and form no part of the claimed design.
